UNITED STATES PATENT OFFICE

133,667

DESIGN FOR AN AMPHIBIAN PLANE

Robert W. Huzzard, York, Pa., assignor of two-thirds to George H. Whiteley, III, York, Pa.

Application July 22, 1941, Serial No. 102,369

Term of patent 14 years

To all whom it may concern:

Be it known that I, Robert W. Huzzard, a citizen of the United States and a resident of York, in the county of York and Commonwealth of Pennsylvania, have invented a new, original, and ornamental Design for an Amphibian Plane, of which the following is a specification, reference being had to the accompanying drawings forming a part thereof.

Figure 1 is a top perspective view of an amphibian plane embodying my new design with the parts thereof shown in flight position,

Figure 2 is a top perspective view of the amphibian plane illustrated in Figure 1 with the pontoons in landing position,

Figure 3 is a bottom perspective view showing the pontoons in landing position,

Figure 4 is a bottom perspective view showing

the wheels in landing position and the pontoons retracted,

Figure 5 is a side elevational view showing the wheels in landing position,

Figure 6 is a side elevational view showing the pontoons in landing position,

Figure 7 is a front elevational view showing the wheels in landing position,

Figure 8 is a front elevational view with the wheels and pontoons retracted to flight position, and

Figure 9 is a front elevational view showing the pontoons in landing position.

I claim:

The ornamental design for an amphibian plane, as shown.

ROBERT W. HUZZARD.
